ABSTRACT OF THE DISCLOSURE

An ellipsoidal compass for selectively drawing either circles or ellipses of varied shapes and sizes, the device comprising a pair of spaced legs extending at an angle respective to each other, the legs being retained to rotate within a circular ring which when being retained in a plane parallel to the drawing surface will cause the compass to draw a circle, but wherein if the ring is inclined at an angle respective to the drawing surface will cause the compass to draw an ellipse, the particular shape of the ellipse being defined by the amount of inclination of the ring.

This invention relates generally to ellipsographs.

A principal object of the present invention is to provide an ellipsoidal compass which may be used selectively for drawing either circles or ellipses.

Another object of the present invention is to provide an ellipsoidal compass which can draw circles of various sizes and ellipses of various sizes.

Yet another object of the present invention is to provide an ellipsoidal compass wherein the ellipses may be made of different relative width to the length thereof which is generally defined as ellipses of a particular angle.

Other objects of the present invention are to provide an ellipsoidal compass which is simple in design, inexpensive to manufacture, rugged in construction, easy to use and efficient in operation.

These and other objects will be readily evident upon a study of the following specification and the accompanying drawing wherein:

FIG. 1 is a perspective view of the present invention shown in operative use;

FIG. 2 is a perspective view of one of the compass legs of the present device;

FIG. 3 is a perspective view of the other of the compass legs;

FIG. 4 is a perspective view of one of the components of the present invention comprising an outer ring;

FIG. 5 is a perspective view of another component comprising an inner ring; and

FIG. 6 is a view of the guide post.

Referring now to the drawing in detail, the reference numeral 10 represents an ellipse-circle drawing instrument according to the present invention wherein there is a compass unit 11 comprised of a long leg 12 and a short leg 13, the legs being pivotable at their one ends about a bearing 14, the ends being maintained in frictional engagement with the bearing by means of a spring 15, as shown in FIG. 1 of the drawing. The bearing 14 includes a pin at one end of a shaft 16 which extends through an opening in the spring 15, the end of the shaft having a handle 17 generally used for swinging the compass.

The opposite end of the leg 13 is provided with a pivotable bearing 18 which is mounted to pivot about a pin 19 extending transversely through the leg 13.

The other leg 12 is provided at its opposite end with an opening into which a shaft 20 is press fitted, the shaft 20 having a slidable stylus 21 carried thereupon. The stylus may either support a pencil lead 22 for purpose of writing upon a drawing surface 23, or it may carry an ink stylus as preferred. The stylus may be secured in a selective posi-

2

tion upon the shaft 20 when used to draw an ellipse or a circle of a selected size. Along an intermediate portion of the leg 12 there is an elongated slot 23 as shown in FIG. 2 of the drawing.

An inner ring 25, shown in FIG. 5 includes a circular rim 26 having a diametrically extending bar 27 thereacross, the bar being integral therewith. The bar 27 is fitted through an opening 28 within the bearing 18 of the compass leg 13, and the bar 27 is additionally fitted through the slot 23 of the other leg 12.

The ring 25 is fitted within a groove of circular configuration within a circular outer ring 29. Thus the outer ring 29 comprises a member that has a hollow, circular recess upon its inner periphery into which the inner ring 25 is fitted and wherein the inner ring is slideable. The outer ring 29 is provided with a pair of outwardly extending shaft stubs 30 located diametrically apart, as shown in FIG. 4. The stub shafts 30 are supported pivotally free within bearings 31 of a V-frame 32 which may be fitted around an upstanding guide post 33. The lower end of the guide post is provided with a needle 34 of relatively short length so as to anchor the same within the surface of the drawing paper.

When it is desired to employ the present device for drawing a circle, the guide post is first set up so as to maintain the instrument in a set location upon the drawing. The stylus 21 is moved along the shaft 20 to a desired position so to get a proper size of circle to be drawn. The outer ring 29 is maintained in a horizontal position relative to the drawing surface, and the compass until 11 is then rotated by means of the handle 17. The stylus will thus draw a true circle. In order to draw an ellipse, the outer ring 29 is tilted respective to the drawing surface so that as the leg 12 rotates, it will move through a relatively long axis which extends across the bearings 31 and which is defined with the reference numeral 35. At this position, the long dimension of an ellipse is drawn. When the compass unit is rotated 90 degrees thereto, the leg will be on a line which comprises a minimum axis due to the tilted outer ring in the bearings 31. Depending on the amount of tilt of the ring, the particular shape of the ellipse will be described. Thus if the ring is tilted to a maximum, the ellipse will have a relatively long axis but a very short axis perpendicular thereto.

It is to be understood that this invention may be modified by employing inner and outer rings which are of ellipsoidal configuration instead of as shown to comprise true circles. Thus an additional assortment of ellipses may be described.

Thus there has been provided an ellipsograph which may draw circles or ellipses of various sizes and of various shapes.

While various changes may be made in the detailed construction, it is understood that such changes will be within the spirit and scope of the present invention as is defined by the appended claims.

I claim:

1. In a circle ellipse drawing instrument, the combination of a compass unit, said compass unit comprising a pair of diverging legs, one end of said legs being pivotable about a bearing, the opposite end of said legs being selectively adjustable apart, and means for confining the distance apart of the other ends of said legs, said means having characteristics for selectively having said compass unit describe a circle or an ellipse, one of said compass legs comprising a short leg and the other of said compass legs comprising a long leg, said short leg having at its opposite end a freely pivotable bearing pivotable about a pin mounted transversely through said leg, said bearing having a central opening therethrough, the other of said compass legs comprising said long leg being pro-

vided with a sidewardly extending shaft affixed thereto, said shaft supporting a slideable stylus thereupon, said stylus carrying a means for drawing upon a drawing surface, an intermediate portion of said long leg having a longitudinally extending slot therethrough, said means comprising an inner ring and an outer ring, said inner ring comprising a circular rim having a diametrically extending bar integral therewith, said bar being received through said slot of said long leg and said opening of said bearing in said short leg.

2. The combination as set forth in claim 1 wherein said outer ring has a circular groove on the inner periphery thereof to receive said inner ring pivotally free therewithin.

3. The combination as set forth in claim 2 wherein said

15 HARRY N. HAROIAN, Primary Examiner

outer ring includes a pair of radially outwardly extending stub shafts retained pivotally free between diverging legs of a V-frame selectively supportable about an upstanding guide post.
